Primary Examiner—Cathron C. Brooks

(57) CLAIM

We claim the ornamental design for a pet storage cabinet, as shown and described herein.

DESCRIPTION

FIG. 1 is a front, left and top perspective view of a pet storage cabinet showing our new design; and,

FIG. 2 is an exploded front, left and top perspective view thereof, with the drawers and door shown separated for completeness of illustration.

The broken lines shown are for illustrative purposes only and form no part of the claimed design.

1 Claim, 2 Drawing Sheets
